UNITED STATES PATENT OFFICE

CLARENCE E. DUNN, OF DAYTON, OHIO

MILK-BOTTLE DEPOSITING AND EMPTY-BOTTLE-COLLECTING DEVICE

Application filed March 29, 1928. Serial No. 265,638.

This invention relates to new and useful improvements in means constructed for permanent arrangement within an opening in an outer kitchen or pantry wall for facilitating the delivery of empty bottles to the outer side of the opening, and the delivery of filled bottles to the inner side of the opening after the empty bottles or filled bottles have been arranged therein, thus overcoming the requirement of the placing of empty bottles upon the kitchen or door step, and also to overcome the necessity of the milk man having to place the bottles upon the door step or having to ring the door bell and having to await the personal taking of the milk by some authorized person.

An important object of this invention is to provide a device of this character wherein the filled milk bottles may be placed within the device from the outer side of the house and wherein the device may be caused to operate to move the bottles into the inner side of the house, automatic means being provided for locking the device against movement after the device has been turned so as to move the filled milk bottles into the inner side of the wall opening within which the device is arranged.

A further object of the invention is to provide a device of this character that is unusually simple in construction, and that may be installed or constructed within dwellings at a very low cost.

In the drawings wherein like reference characters indicate corresponding parts throughout the several views:

Figure 1 is a fragmentary vertical section through an outer building wall within which is arranged a device constructed in accordance with the present invention.

Figure 2 is a horizontal section taken substantially upon the line 2—2 of Figure 1 and looking downwardly in the direction of the arrows.

Figure 3 is a bottom side perspective of a pivotal milk bottle tray within which one of the filled milk bottles is to be disposed by the dairy man.

Figure 4 is a top side perspective thereof.

Figure 5 is a horizontal section taken substantially on the line 5—5 of Figure 1.

Figure 6 is a fragmentary bottom plan view of the device, and

Figure 7 is a fragmentary section through the milk tray at one side of the device taken substantially upon the line 7—7 of Figure 2.

Now having particular reference to the drawings, 5 designates fragmentarily the outer building wall of a pantry, kitchen, or cook room of a dwelling constructed with a relatively large opening therethrough, and within which is arranged a telescopic sectional housing 6 of predetermined dimension. Arranged perpendicularly within the center of this housing is a partition wall 7 preferably consisting of a pair of metallic plates 8—8 maintained in spaced parallel relation by a filler 9 of asbestos, felt, rubber or other suitable material. This filler projects at its opposite ends beyond the ends of the plates 8—8 so as to engage the opposite vertical sides of the housing 6 when the partition wall is in true longitudinal position within the center of the housing to prevent the passage of air between the side walls of the housing and the opposite ends of this partition, see Figure 2.

The lower ends of the plates 8—8 forming the partition wall 7 are formed or constructed with outwardly extending semi-circular trays 9—9' that have spaced relation with respect to the bottom wall of said housing 6, see Figure 1. At opposite ends of these trays 9—9' the same are formed with circular de-

pressions to provide pockets 10 for the reception of milk bottles, said pockets surrounded by upstanding clips 10a designed to bear against and hold bottles. However, pivoted to the opposite sides of the partition 7 directly above these trays 9—9' and intermediate the endmost pockets of each tray is an arm 11 formed at its outer end with a small circular tray 12 for receiving a milk bottle.

Between each circular tray 12 and the tray 9' directly therebeneath is an expandable coil spring 13 for normally maintaining the small tray 12 in considerable spaced relation with the main tray 9' therebeneath. Furthermore, directly forwardly of the spring 13 each tray 12 is equipped with a depending pin 14 mov-

able through an opening 15 in the main tray 9' for a purpose hereinafter more fully described.

The lower edge of the partition wall 7 is formed intermediate its ends with a pintle 16 that is freely rotatable through an opening in the bottom wall of the housing 6, the lower end of this pintle being equipped with a small gear 17. Said pintle 16 is equipped with a flange 16a attached to the adjacent tray 9', and between said flange 16a and a circular race in the bottom wall of the housing 6 are arranged anti-friction balls 17a designed to render easy the turning of the trays 9'. Mounted upon a stub shaft depending from the bottom wall of the housing 6 is a larger gear 18 that has mesh with said gear 17 as clearly disclosed in Figure 1. Disposed over these gears is a suitable housing 19, while said stub shaft of the gear 18 projects through the bottom wall of the housing and is attached to a lever 20 that extends toward the outer side of the wall 5, the outer end of this lever being freely movable through a horizontal slot formed in the outer side of the wall 5 as disclosed in Figures 1, 5 and 6. Obviously the swinging of this lever 20 from one side of the housing 5 to the opposite side thereof will cause a one-half rotation of the partition wall 7 and its associated trays 9'-9' so that the empty milk bottles at the inner side of the device will be moved to the outer side thereof to permit the dairyman to collect the same. By the same token any filled bottles disposed within the outer compartment of the device by the dairyman will be moved into the building by the rotation of the device through the medium of the lever 20 which is of course operable by the milk man.

The bottom wall of the housing 5 is formed at its top side with a circular ridge 22 while at the center of the inner compartment said ridge is formed with a notch 23. The strength of the small tray supporting springs 13 is not sufficient to cause the complete depression of the trays 12 when an empty milk bottle is arranged thereon as disclosed by the dotted lines in Figure 1, and obviously the pin of the tray upon which the empty milk bottle is supported will not engage within the notch 23 of the ridge 22 and prevent the proper operating of the device. Thus when empty milk bottles are arranged within the pockets 10-10 and upon the small tray 9 at the inner side of the device the mechanism may be operated by the milkman at the outer side of the building for rotating the partition wall 7 and its associated trays to cause the movement of the empty milk bottles to the outer side of the building. These empty bottles are then removed and filled bottles are arranged in their stead. If only one bottle is to be served to the particular customer, this bottle is arranged upon the pivotal tray 12.

65 The weight of the bottle together with its

contents will depress the spring 13 so that the pin 14 will ride upon the ridge 22 of the housing. As soon as the lever has been moved from one side to the other causing the inward turning of the filled milk bottles, the said pin 14 will engage within the notch 23, thus locking the device against further rotation so as to prevent the filled bottles from being taken by unauthorized parties.

70 It will thus be seen that I have provided a highly novel, simple and extremely useful milk bottle depositing and collecting device that is well adapted for all the purposes heretofore designated, even though I have herein shown and described the invention as consisting of certain detail structural elements it is nevertheless to be understood that some changes may be made therein without affecting the spirit and scope of the appended claims.

75 Having thus described the invention, what I claim as new is:—

80 1. In a bottle depositing and collecting device for arrangement within an outer building wall, a housing arranged within the building wall and open at its opposite ends, a perpendicular wall arranged within the center of the housing, and mounted for rotation within the housing, milk bottle supporting means associated with opposite sides of the perpendicular wall, means at the outer side of the building wall whereby the perpendicular wall and said milk bottle supporting means may be rotated, and automatic means for locking the wall against rotation after filled milk bottles have been disposed upon the bottle supporting means at the outer side of the perpendicular wall and the wall rotated to move the filled milk bottles to the inside of the building.

85 2. In a bottle depositing and collecting device for arrangement within an outer building wall, a housing arranged within the building wall and open at its opposite ends, a perpendicular wall arranged within the center of the housing, and mounted for rotation within the housing, milk bottle supporting means associated with opposite sides of the perpendicular wall, means at the outer side of the building wall whereby the perpendicular wall and said milk bottle supporting means may be rotated, and automatic means for locking the wall against rotation after filled milk bottles have been disposed upon the bottle supporting means at the outer side of the perpendicular wall and the wall rotated to move the filled milk bottles to the inside of the building, said means consisting of a pan pivoted to the wall and adapted to receive a filled milk bottle, and means depending from the pan for engagement within a notch formed in the bottom of the said housing at the inner side of the perpendicular wall in a manner and for the purpose described.

3. In a milk bottle depositing and collecting device for disposition within an outer building wall, a housing constructed for arrangement within the building wall and open at its opposite ends, a rotating unit mounted within the housing and consisting of a central perpendicular wall, a milk bottle pan pivoted to each side of the perpendicular wall, means operable from the outside of the building wall to cause the rotation of said rotary unit, and means between the pan and the housing at the inner side of the perpendicular wall to cause the locking of the rotary unit against rotation when the full milk bottles have been moved into the inner end of the housing.

4. In a milk bottle depositing and collecting device for disposition within an outer building wall, a housing constructed for arrangement within the building wall and open at its opposite ends, a rotating unit mounted within the housing and consisting of a central perpendicular wall, a milk bottle pan pivoted to each side of the perpendicular wall, means operable from the outside of the building wall to cause the rotation of said rotary unit, means between the pan and the housing at the inner side of the perpendicular wall to cause the locking of the rotary unit against rotation when the full milk bottles have been moved into the inner end of the housing, said means consisting of a pin depending from the pan, a spring arranged beneath the pan for normally maintaining the pin out of engagement with the housing bottom wall, said spring being overcome by the weight of a full milk bottle disposed within the pan so that the pin will engage said housing bottom wall, and enter a notch in the bottom wall when the pan carrying the full milk bottle is at the inner end of the housing.

5. In combination, a housing with open outer and inner ends, a turnable unit in said housing and having a partition adapted in one position to close the housing and also having portions at opposite sides of said partition, vertically movable supports on said portions and having detents, a stationary keeper complementary to said detents and arranged adjacent to the inner end of the housing and means for maintaining the supports against downward movement save when one of the detents is in vertical coincidence with said keeper and is permitted to move downwardly into the same.

6. In combination, a housing with open outer and inner ends, a turnable unit in the housing and having a partition adapted in one position to close the housing, a vertically movable support connected with and turnable with said partition, and also movable vertically and having a detent, a stationary keeper complementary to said detent and arranged adjacent to one end of the housing,

and means for preventing downward movement of said support save when said detent is in vertical coincidence with the keeper and is permitted to move downwardly into engagement with the keeper.

In testimony whereof I affix my signature. 70
CLARENCE E. DUNN.
